REPLACEABLE FUSE PLUG

Ora G. Vanderveer, Kansas City, Mo.

Application August 28, 1937, Serial No. 161,427

10 Claims. (Cl. 200—130)

My invention relates to fuse plugs, and more particularly to a fuse plug having a replaceable fusible element.

It is a purpose of my invention to provide a fuse plug of the above mentioned character that is simple in construction and which is easy to assemble, and which has a fusible element that can be easily removed after the fuse has blown and readily replaced.

10 More particularly my invention comprises a fuse plug having an insulating body portion that is recessed and in which a fusible element can be mounted, and which comprises a pair of contact members with which the fusible element is detachably engageable, said contact members being yielding and being mounted in a simple manner on the insulating body portion.

It is a further purpose of my invention to provide a fuse plug of the above mentioned character, in which a transparent cap, or cover portion, is provided, that is detachably connected with the insulating body portion and which is, preferably, made of glass, the fusible element being so mounted in the fuse plug that it can be readily seen through the glass cap member to determine the condition thereof, that is, whether the fuse has been blown or is intact. Such glass cover members are discolored or burnt by the flame resulting from the blowing of the fuse and are frequently difficult to see through because of this condition. It is one of the purposes of my invention to provide protective means in the form of a detachably mounted sheet of mica for preventing such discoloration or burning of the inner face 35 of the glass cap member. In order to facilitate the viewing of the condition of the fusible element, the glass cover member is, preferably, provided with a curved surface, which makes the main body portion thereof act as a lens, magnifying the size of the fusible element so as to make the condition thereof more readily determinable.

It is a further purpose of my invention to provide means for bending the normally flat fuse element into contact with the yielding contact members mounted in suitable passages in the body portion of the fuse plug. Said means, preferably, comprises an insulating member that is of a tubular character, or has a longitudinal passage therethrough, which is located between the cap portion and the fusible element, and through the opening in which the fusible element can be viewed by looking through said transparent cap portion, said member also acting to hold the fuse element in contact with said yielding contact members 55 after the same has been put in position between

the cap member and the body portion and within the recess provided therefor in the body portion and said cap member has been secured to said body portion.

It is another important feature of my invention to provide a fuse plug of the above mentioned character, in which the fusible element is entirely enclosed within the fuse plug, that is, housed between the body portion and the cap portion, the fusible element being so mounted that the same will be spaced from the base portion and the cap portion at the point where the flame usually will occur when the fusible element fuses, or the fuse is blown.

It is a particularly important purpose of my invention to provide a fuse plug of the above mentioned character that is so constructed that the fusible element can be merely dropped into the same and will seat itself in proper position to be acted on by the member that bends the same into its operative shape and into contact with the yielding, or resilient, contact members, and in which said member that shapes the fuse into its proper form to engage with the yielding contact members is so constructed that the same will automatically position itself properly relative to the fusible element, so that upon pushing of the same toward the body portion, the fusible element will be bent at its ends into contact engaging position, said insulating member engaging the fusible element being so constructed and arranged that the same will be held in its final position, with the fusible element in firm contact with the yielding contact members, by means of the cap member when the cap member is in engagement with the body portion.

It is another purpose of my invention to provide a fuse plug of the above mentioned character, which, after removal of the cap portion and contact bending member, is adapted to provide for the easy removal of the fusible element by merely shaking the same out of its position in the fuse plug.

Other objects and advantages of my invention will appear as the description of the drawings proceeds. I desire to have it understood, however, that I do not intend to limit myself to the particular details shown or described, except as defined in the claims.

In the drawings:

Fig. 1 is a side elevation of my improved fuse plug, slightly enlarged.

Fig. 2 is a longitudinal sectional view thereof, which is taken on a line corresponding substantially to the line 2—2 of Fig. 6.

50

55

Fig. 3 is an end view of the plug at the cap end thereof.

Fig. 4 is a section taken substantially on the line 4-4 of Fig. 2, the filament shaping member being omitted.

Fig. 5 is a perspective view of the filament shaping member.

Fig. 6 is a longitudinal sectional view taken substantially on the line 6-6 of Fig. 1.

Fig. 7 is an end elevation of the plug as viewed from the socket engaging end thereof, partly broken away.

Fig. 8 is a section taken substantially on the line 8-8 of Fig. 2.

Fig. 9 is a fragmentary side elevational view, partly broken away, of the body portion and cap portion of the fuse plug, and

Fig. 10 is a fragmentary sectional view, similar to Fig. 2, but with the cap portion omitted and the fuse element shaping member shown in the position it assumes prior to the bending of the fuse, but after having been placed in contact with the fuse element.

Referring in detail to the drawings, my improved fuse plug having a replaceable fusible element, comprises a body portion 11 of insulating material, which is provided with a central projection 12 at one end thereof and with a large recess 13 in the other end thereof. The body portion is provided with a somewhat flared wall at 14 at the end thereof opposite that having the projection 12. A pair of longitudinal passages 15 of a slot-like character are provided, extending through the end of the body portion 11 adjacent the projection 12. A contact member 16 having a recurved, or hook-like, end portion 17 thereon extends into one of the passages 15 and substantially through the same, said contact member 16 having an end portion 18 overlying the end of the projection 12 and secured thereto by means of a rivet 19, which is embedded in the material of the projection 12 and is headed over by expanding the same, as indicated at 20, to secure said contact member to the end portion of said central projection 12, said portion 18 of the contact member thus forming the center contact of the screw plug type of fuse plug that is illustrated.

A contact member 21 is mounted in the other passage 15, said contact member 21 having an arcuate portion 22 that overlies the end portion of the main body portion 11 of the fuse plug, but is spaced from the center contact 18 and has end enlargements 23, through which the rivets 19 extend, the same being headed by expansion thereof at 20 in the manner previously described, and being embedded in the body portion 11 of the fuse plug. The arcuate portion 22 of the contact member 21 overlies a flange 24 on the screw shell 25, said screw shell snugly fitting the smooth or unthreaded cylindrical outer surface of the body portion 11, being adapted to be slid into place with the flange 24 in engagement with the end wall of the body portion 11 and held from movement away from the body portion by the arcuate portion 22 of the contact 21 and rivets 19. The member 12 is grooved at 25 to permit the enlargements 23 on the portion 22 and the enlargements 26 on the flange 24 to be slid into position, said enlargements 26 cooperating with the grooves 25 to hold the screw shell 25 against turning on said body portion 11.

Said contact 21 is provided with a recurved, or hook-like, end portion 17, made identically the same as is the hook-like end portion of the contact 16. The contact members 16 and 21 are

somewhat resilient, so as to have a spring, or yielding, action and are shaped so as to tend to move away from the central portion of the body portion 11, or in other words, away from each other. It will be obvious that the contact members are easily put in position by merely pushing the same through the passages 15 and securing the rivets 19 in position in the manner shown. The rivets can be either molded in the body portion, or in any other manner secured therein, and if molded therein, will, of course, form tubular projections on the body portion, which are merely expanded or headed over after the screw shell and contacts are put in place to secure said parts in proper position.

The recess 13 is provided with a projecting portion 26, which is of substantially an annular character, as will be evident from Fig. 8, having a central opening 27 therein, said projection and said central opening being located substantially concentrically about the longitudinal axis of the body portion of the plug. The recess 13 flares, or enlarges, in its dimensions toward the open end thereof and comprises a pair of transversely concave longitudinally flaring wall portions 28, and a pair of substantially transversely straight longitudinally flaring wall portions 29, which extend from the end edge portion of the body portion 11 at the open end thereof to the bottom of the groove 30 surrounding the projection 26. The projection 26 also has a pair of transversely aligned grooves 31 therein that extend radially from the axis of the plug, said grooves being adapted to receive a fusible element 32, said fusible element, preferably, having a reduced central portion 33 of such cross section as to give the proper capacity to the fuse, so that it will blow or ignite at the said narrow portion 33 when current in excess of the amount for which the fuse is designed, passes through the circuit in which the fuse is located. In Fig. 4 the fuse is shown in position in the grooves 31 and resting on the annular member 26. The slot-like passages 15, it will be noted, are located below the fuse and the spring contacts are in position ready to be engaged by the fusible element.

In Fig. 10 the same position of the fusible element is shown as that shown in Fig. 4, but the element of insulating material used for bending the fusible element into position in engagement with the contacts 17, provided on the end of the contact members 16 and 21, is shown resting thereon. The insulating member for bending the fusible element into its operative position in engagement with the contact members that connect the same in the circuit, is shown removed from the fuse plug in Fig. 5. It comprises a tubular body portion 34, which has a small end 35 that is provided with a ring-like annular enlargement thereon, so that the same can be readily engaged by the fingers, and a larger end, which has a pair of concavo-convex walls 36 and a pair of flat walls 37. The body portion having a flaring curved connecting portion between the ringlike bead portion 35 at one end thereof and the enlarged end having the concave outer walls and flat outer walls, above referred to. The concavo-convex walls 36 correspond substantially in external contour to the curvature of the concave walls 28 and the flat walls 37 are of such shape that the same will fit between the flat wall portions 29 when the reduced sharpened end edge portion 39 of said member 34 engages the shoulder 40, provided within the recess 13 adjacent the longitudinal

passages 15. Also the length of the outer surfaces of the walls 37 is such that these will fit between the bottom portions of the curved walls 28 without wedging therebetween.

5 It will accordingly be seen that, due to the shape of the walls of the recess 13, the fusible element 32, if dropped into the recess 13, will drop onto the central annular projection 26 extending into said recess, and due to the relative 10 size of said annular projection 26 and the wall portions 29 near the bottoms thereof, said fusible element cannot fall off the annular projection 26, and with a little shaking of the body portion, the fusible element 32 will seat itself 15 in the recesses 31. It will also be noted that the member 34 can be dropped into the recess 13 and will guide itself into the position shown in Fig. 10, due to the shape thereof and the shape of the walls of said recess 13. It will 20 also be evident that if the finger of the operator of the device is pushed against the end portion of the member 34 having the bead 35, the same can be utilized as a tool to bend the fusible element from the position shown in Fig. 10 to 25 that shown in Fig. 2, with the end portions 41 of the fusible element bent into the position shown in Fig. 2, between the inner faces of the flat wall portions 37 and the outer sides of the hook-like, or recurved, contacts 17 on the contact 30 members 16 and 21.

The body portion 11 is provided with a transparent cap member 42, which is detachably connected therewith by a suitable quick acting interlocking connection, which also tightly wedges 35 the closure member in position on the body portion. The member 42 is, preferably, made of glass and has a slightly recessed central portion 43 that is provided with a convex surface 44, serving as a lens to enlarge the fusible element as viewed through the central passage, or 40 opening, 45 in the member 34. An annular shoulder 46 is provided on the body portion 11 near the open end thereof, and a plurality of curved interrupted flanges 47, having inclined 45 faces 48 are also provided on said body portion, said flanges 47 cooperating with inwardly directed lugs 49 on the depending flange 50 of said cap portion 42, so that said cap portion 50 may be placed in position on the body portion 11 with the interrupted flanges 47 out of alignment with the lugs 49, and then turned to force the cap member 42 down tightly on the body portion 11. The placing of the cap member 42 in position can be utilized to force the insulating 55 member 34 downwardly into engagement with the fusible element 32 to bend it into the position shown in Fig. 2, and, of course, said member 34, after the cap 42 is interlocked with the body portion, will hold the member 34 in the 60 position shown in Fig. 2 and the fusible element in engagement with the contacts 17. A roughened or knurled portion 51 is, preferably, provided on the outer side of the flange 50 to facilitate turning thereof.

65 It will be noted that an air space is provided around the fusible element at the reduced portion 33 thereof, so that there will be no contact of the fusible element with any portion of the mounting therefor at the place where the fuse 70 will blow when the current passing through the same exceeds the amount for which the fuse is designed. However, a flare of flame may strike the inner face of the glass cover or cap member 42 and discolor the same and thus make it 75 difficult to see through the same to inspect the

fuse to determine the condition of the fusible element 32. In order to prevent this, a sheet of transparent material 53 is provided, which is located between the smaller end of the member 34 and the inner face of the cap 42, said sheet 5 of material 53 being of a non-combustible character, such as mica, for example, and, preferably, a plurality of such sheets 53 of mica being furnished with a predetermined number of fuse elements, in order that a discolored mica 10 sheet 53 may be replaced readily with a clear one, should it have become discolored by the blowing of a fuse. The mica sheet 53 is merely laid in position on the end 35 of the member 34 before the cap is put in position, and will, 15 of course, be firmly held in position between the cap member and the member 34 after the parts are in the assembled position shown in Fig. 2.

What I claim is:

1. In a fuse plug, an insulating body portion, 20 a cap portion, means for detachably connecting said portions, contacts mounted in said body portion, a straight, strip-like, ductile, fusible element, and a removable die member mounted between said cap and body portions for bending said strip- 25 like element out of normal shape into contact engaging position and holding said element in such position.

2. In a fuse plug, an insulating body portion, a cap portion, means for detachably connecting 30 said portions, contacts mounted in said body portion, a ductile fusible element, said body portion having a seat for said fusible element, and a member of insulating material detachably mounted between said cap and body portions and 35 having die means thereon cooperating with said seat to bend the ends of said fusible element into contact engaging position and holding said element in such position.

3. In a fuse plug, an insulating body portion 40 having a recess therein, a cap portion, means for detachably connecting said portions, contacts mounted in said body portion, a strip-like fusible element, said body portion having a seat receiving said strip-like element in said recess and having 45 converging wall portions for guiding said strip-like element into engagement with said seat upon the same being dropped into said recess, and a member of insulating material detachably mounted between said cap and body portions and 50 having means thereon engaging said strip-like element to bend the same around said seat into contact engaging position and holding said element in such position.

4. In a fuse plug, a recessed insulating body 55 portion, a cap portion, means for detachably connecting said cap and body portions, yielding contacts mounted in said body portion, a fusible element, said body portion having a recess therein having a projecting seat for said fusible element 60 adjacent said contacts, and a member of insulating material detachably mounted in the recess in said body portion and having means thereon engaging said fusible element and embracing said seat to bend said fusible element into engagement with said contacts, said body portion having means for guiding said fusible element into position on said seat and for guiding said member of insulating material into embracing 65 relation to said seat and into a predetermined 70 position relative to the fusible element on said seat, said cap portion engaging said member of insulating material to hold said insulating member in engagement with said fusible element and 75

- said fusible element in engagement with said contacts.
5. In a fuse plug, an insulating body portion, a cap portion, means for detachably connecting said portions, contacts mounted in said body portion, a fusible element, said body portion being recessed and having a projecting seat for said fusible element in said recess, and a tubular member of insulating material detachably mounted between said cap and body portions and having means thereon for bending said fusible element into contact engaging position and embracing said seat at one end thereof to hold said element in such position, said fusible element being completely housed within said plug by said projecting seat of said cap and body portions and confined between said body portion and the end of said member of insulating material embracing said seat.
6. In a fuse plug, an insulating body portion, a glass cap portion embracing one end of said body portion, means for detachably connecting said portions, contacts mounted in said body portion, a strip-like fusible element, a tubular member mounted between said cap and body portions for bending said strip-like element into contact engaging position and holding said element in such position, and a mica shield between said glass cap portion and said tubular member.
7. In a fuse plug, a recessed insulating body portion, a transparent cap portion, means for detachably connecting said cap and body portions, yielding contacts mounted in said body portion, a fusible element, and a tubular member of insulating material detachably mounted in the recess in said body portion and having means thereon engaging said fusible element to bend said fusible element into engagement with said contacts, said cap portion engaging said member of insulating material to hold said insulating member in engagement with said fusible element and said fusible element in engagement with said contacts.
8. In a fuse plug, an insulating body portion, a cap portion, means for detachably connecting said portions, contacts mounted in said body portion, a strip-like fusible element and means mounted between said cap and body portions for bending said fusible element into contact engaging position and holding said element in such position, said strip-like element being free of said body portion and said bending means to permit said element to be shaken out of said body portion upon detachment of said cap portion and removal of said means from said body portion.
9. In a fuse plug, a recessed insulating body portion, a glass cap portion, means for detachably connecting said cap and body portions, yielding contacts mounted in said body portion, a fusible element, a tubular member of insulating material detachably mounted in the recess in said body portion and having means thereon engaging said fusible element to bend said fusible element into engagement with said contacts, said cap portion engaging said member of insulating material to hold said insulating member in engagement with said fusible element and said fusible element in engagement with said contacts, and a mica shield between said glass cap portion and said fusible element.
10. In a fuse plug, an insulating body portion, a cap portion, means for detachably connecting said portions, said body portion having a pair of longitudinal passages therein, contacts mounted in said passages having U-shaped end portions, a screw shell carried by one of said contacts engageable with said body portion by relative longitudinal sliding movement, a center contact carried by the other of said contacts, expandable rivets securing said screw shell and center contact to said body portion, a fusible element, and means mounted between said cap and body portions for bending said fusible element into engagement with the U-shaped ends of said contacts and holding said element in such position.

ORA G. VANDERVEER.
